(57) **CLAIM**

The ornamental design for a gas line holder, as shown and described.

DESCRIPTION

FIG. 1 is a perspective view of a gas line holder showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the figures represent portions of the article that form no part of the claimed design.
